DELAYED ACTION ATTACHMENT FOR
PRINTING PRESS GRIPPERS

Clarence B. Kliever, Elk River, Minn.

Application January 30, 1950, Serial No. 141,270

4 Claims. (Cl. 101—408)

1

This invention relates to new and useful improvements in printing presses of the bed and platen type equipped with a mechanism for automatically feeding the blank sheets into printing position between the usual bed and platen of the press in a manner well known in the art. The platens of many such printing presses are also now equipped with delayed action grippers arranged to continue to hold each printed sheet in contact with the platen during movement of the platen from its closed or printing, to its open position, to enable the usual suction grippers of the device for receiving the printed sheets to positively grip each sheet and eject it from the press, and whereby the press may be operated at high speed.

There are however, a great many conventional printing presses in use at the present time which are not equipped with delayed action grippers, whereby such presses must be operated at a relatively lower speed to allow ample time for delivering each printed sheet in position to be engaged by the usual suction grippers of the press. Because of the relatively lower speed to which these presses must be operated, the resultant capacity of such machines may be considerably lower than the capacity of machines equipped with delayed action grippers, as hereinbefore referred to, and it is therefore highly desirable that means be provided whereby such lower speed presses may be converted into high speed machines, to enable them to compete with modern high speed machines.

One of the important objects of the present invention therefore is to provide an attachment for delaying the opening or paper releasing action of the platen grippers of a press whose grippers were not originally designed for such delayed action, whereby the usual grippers of the press are retained in gripping engagement with the printed sheet on the platen during movement of the platen from printing or closed position, to its open position, thereby to prevent displacement of the printed sheet during such movement, and whereby the speed of such a press may readily be increased to the extent that the output of the machine may compare favorably with the output of modern high speed presses now in common use.

A further object of the present invention is to provide an attachment comprising a plurality of cams and rollers having means for mounting them on the usual platen operating mechanism of a conventional low speed press, whereby the usual platen grippers will be given a delayed action,

2

to thereby retain the printed sheet upon the platen as the platen returns to its normal open position, whereby the suction grippers of the delivery device for removing the printed sheet from the platen, may engage the sheet before the grippers release it and thus prevent displacement of the sheet on the platen from the time it is initially placed thereon to receive an impression until the printed sheet is removed from the press.

10 Another object is to provide such an attachment which is extremely simple and inexpensive in construction, and which is so constructed that it may readily be attached to a conventional slow speed press substantially without requiring any alterations in the press, thereby to cause the usual grippers of such a press to operate with a delayed action in a manner very similar to that of modern high speed presses.

Other objects of the invention reside in the 20 simplicity of the invention which embodies a minimum number of parts, all of which may readily be secured in position on the usual operating arms and linkage of the press, whereby the usual platen grippers of a press which previously were 25 not capable of delayed action, will operate with a delayed action, whereby the speed of such a press may be greatly increased; and in the provision of such an attachment which comprises a minimum number of parts so constructed and arranged that the attachment may readily be attached to the press without requiring any major alterations thereto.

30 These and other objects of the invention and the means for their attainment will be more apparent from the following description taken in 35 connection with the accompanying drawings.

In the accompanying drawings there has been 40 disclosed a structure designed to carry out the various objects of the invention, but it is to be understood that the invention is not confined to the exact features shown, as various changes may be made within the scope of the claims which follow.

45 In the drawings:

Figure 1 is a side elevational view of a conventional printing press showing the invention embodied therein;

50 Figure 2 is a plan view of the platen on a larger scale, with parts of the press omitted, and showing the grippers in operative engagement with a printed sheet supported thereon, and the suction grippers of the delivery device engaged with the sheet;

55 Figure 3 is a fragmentary detail sectional view substantially on the line 3—3 of Figure 7, show-

ing the relative positions of the various cams and rollers constituting the invention;

Figure 4 is a fragmentary view showing the parts in the positions assumed when a sheet is receiving an impression;

Figure 5 is a similar view showing the position of the parts when the platen commences its movement toward open position;

Figure 6 is a view similar to Figure 5 showing the platen further advanced in its movement toward open position;

Figure 7 is a view showing the platen in its open position with the grippers still engaged with the printed sheet supported thereon, and the suction grippers of the delivery means also engaged with the sheet;

Figure 8 is a view showing the platen in wide open position, with the platen grippers open to permit pneumatic grippers of the delivery means to remove the printed sheet from the platen to complete the cycle;

Figure 9 is an enlarged fragmentary view showing the bracket for adjustably securing one of the rollers of the attachment to the side arm of the press;

Figure 10 is a detail sectional view on the line 10—10 of Figure 8; and

Figure 11 is a perspective view of the composite cam unit, detached from the machine.

In the selected embodiment of the invention herein disclosed, there is illustrated in Figure 1, a side elevational view of a conventional form of printing press with the invention embodied therein. To simplify explanation, some of the operating parts of the press are not shown.

The printing press comprises a main frame 1 having a bed 2 mounted for pivotal movement about the usual bed shaft 3, shown in Figure 1. The press also includes the usual platen 4, shown in full and dotted lines in Figure 1; a stock magazine, generally designated by the numeral 5; a sheet feeding mechanism indicated by the numeral 6, and a sheet delivery mechanism 7.

The sheet feeding mechanism is shown comprising a pivotally mounted suction arm 8 carrying a number of suction feed grippers 9, adapted to engage and grasp the foremost sheet in the magazine 5 and deliver it onto the platen 4, when the latter is supported in its open position; as indicated in dotted lines in Figure 1. The platen 4 is mounted for rocking movement on trunnions 11, by suitable means not deemed necessary to illustrate in the drawings, it being understood, however, that the platen operates in timed relation to the swinging movement of the bed frame 2 and the operation of the various grippers of the machine.

The stock magazine 5 is shown comprising an inclined table 12 mounted for swinging movement upon an upright member 13 suitably supported in the machine. The magazine 5 has a back rest 14 arranged for sliding movement on the table 12, and adapted to be advanced by suitable means such as a rocker member 15, indicated in Figure 1, and well known in the art.

The bed frame 2 is of conventional construction, and is pivotally supported upon the bed shaft 3, as hereinbefore stated. It carries the usual bed plate 17, ink plate 18, and inking devices 19. The inking devices are arranged to travel over the bed plate 17 during each cycle of operation, thereby to apply the necessary ink to the type of the bed plate to make the desired impression upon the sheet to be printed.

There are now a great many printing presses

of this general type in daily use in which the grippers for supporting the sheet on the platen during the printing operation, do not have a delayed action. In other words, when the sheet 5 has been printed and the bed plate 17 swings out of printing engagement with the platen to permit the latter to be swung to its open position, indicated in dotted lines in Figure 1, the pivoted grippers 21 of the platen 4, shown in Figures 2 and 8, are usually actuated to release the printed sheet before the pneumatic grippers 22 of the sheet delivery mechanism 7 move forwardly to engage the sheet.

To thus release the printed sheet before the usual pneumatic grippers of the sheet delivery mechanism 7 actually engages the printed sheet, has been found objectionable, in that it limits the speed of the machine with a resultant reduction in its capacity. In other words, when operating 10 a printing press wherein the platen grippers do not have a delayed action, it is usually necessary to have an attendant at the machine to constantly watch the printed sheets as they are released from the delivery mechanism, because 15 should the pneumatic grippers 22 of the delivery mechanism fail to properly engage the printed sheets, said sheets may become damaged to the extent that they may be unfit for use.

The novel attachment herein disclosed, when 20 applied to a printing press of the type above referred to, imparts to its grippers 21, a delayed action similar to that now employed in modern high speed printing presses, whereby each printed sheet is retained in position on the platen 4 during 25 the opening movement of the platen so that the pneumatic grippers of the delivery mechanism may engage each sheet thus supported on the platen, and assure proper withdrawal of the printed sheets from the press. The delayed action thus imparted to the platen grippers 21 makes it possible to increase the speed of the press to that of modern high speed presses, whereby its capacity is similarly increased.

The novel attachment herein disclosed is clearly illustrated in the application drawings, and comprises a composite cam unit, generally designated by the numeral 23, shown mounted on a pivot bolt 24, secured in a bracket 25 which in turn is secured to one of the side frame members 26 of the machine frame 1, as best shown in Figure 3. The cam 23 is provided with multiple cam faces 27, 28 and 29. The cam faces 28 and 29 are disposed in a common plane and the cam face 27 is offset from the plane of the cam faces 28 and 29, as illustrated in Figures 2 and 3.

A side arm 31 has one end supported on a crank pin 32 secured in a crank wheel or disk 33 of the press. The crank disk 33 is mounted upon and secured to a main shaft 34, journaled in suitable bearings provided in the machine frame 1. The opposite end of the side arm 31 is pivotally connected to the usual roller frame member 35, one end of which may be connected to the main frame of the machine by a side link 36, shown in Figure 1. The side arm 31, as a result of its connection with the crank wheel or disk 33, imparts pivotal movement to the bed 2 when the machine is in operation. As a result of such oscillation or pivotal movement of the bed 2, and because of the roller frame member 35 being pivoted thereto, the roller frame member 35 is actuated to cause the ink devices 19 to travel downwardly over the face of the bed plate 17 to ink the type secured thereto during each cycle of operation, as is well known in the art.

A link, generally designated by the numeral 37, is shown having its upper end pivoted to a lug 38 on the platen 4, whereby longitudinal movement is imparted to the link 37 when the platen moves from open to closed position, and back, as will be understood by reference to Figures 4 and 7. The lower end of the link 37 has an elongated slot 39 therein, which receives a pin 41 secured in the machine frame, whereby the lower end of the link 37 is guided in its longitudinal movements, as the platen swings from open to closed position, or vice versa.

The link 37 constitutes a part of the printing press, and serves to swing the platen grippers 21 into gripping engagement with the sheet to be printed, when the platen assumes its closed position, as shown in Figures 1 and 4. A suitable spring 23, indicated in Figure 3, constantly urges the grippers 21 into paper gripping relation with the platen 4, as will subsequently be described.

The grippers 21 of the platen are shown secured to a gripper supporting bar 42 having opposed terminals 43 rotatably mounted in suitable bearings 44 secured to the ends of the platen, as clearly illustrated in Figures 2, 3 and 8. The platen supporting bar 42 has an arm 45 depending therefrom, on the lower end of which an anti-friction roller 46 is mounted. The roller 46 is arranged to engage the cam face 47 of the link 37. The cam face 47 is shown having a recess 48 therein adapted to receive the anti-friction roller 46 of the arm 45, when the parts are positioned, as shown in Figures 4 and 5, or in other words, when the platen is in its closed, or in printing position relative to the bed plate 17, as illustrated in Figures 1 and 4. The above described structure is well known.

To delay the opening action of the platen grippers 21, means is provided for preventing pivotal movement of the grippers relative to the platen 4, when the platen moves from its closed printing position, shown in Figure 4, to its open position shown in Figures 7 and 8. Such means is shown comprising an arm 49 which is fixed to the depending arm 45 of the gripper supporting bar 42 of the platen. Arm 49 carries at its outer end a small anti-friction roller 51, positioned to engage the cam face 27 of the multiple cam unit 23, when the platen moves from closed to open position, whereby the platen grippers 21 are retained in paper gripping position, as may be best understood by reference to Figures 6 and 7. This results because during such movement of the platen from closed to open position, cam face 27 engages roller 51 and thus prevents gripper roller 46 from entering recess 48 in cam bar 37, as best shown in Figure 7.

When installing the attachment on a press, the cam unit 23 is laterally offset from the plane of the link 37, as shown in Figure 3. This makes it necessary to outwardly space the roller 51 from the arm 45, as shown in Figure 3. The arm 49 is therefore shown secured to one end of a small shaft or rod 52 having its opposite end fixed in a bracket 53, shown secured to the arm 45 by a suitable clamping plate 54 and screws 55. The cam unit 23 has one end of a suitable spring 50 connected thereto, the opposite end of which is attached to a fixed element on the machine frame, as indicated in the drawings, whereby the spring constantly urges the cam unit in a direction towards the crank disk 33.

To retain the platen grippers 21 in their closed positions, as indicated in Figures 5 and 6, means is provided for retaining the cam unit 23 in the

position shown in Figures 5 and 6, wherein it will be noted the terminal 60 of the cam unit is spaced from the periphery of the crank disk 33. When the platen is in its closed or printing position, shown in Figures 1 and 4, the terminal 60 of the cam unit 23 is engaged with the periphery of the crank disk 33, as shown in Figures 1 and 4.

The means provided for swinging the cam 23 in a direction away from the crank disk 33 to 10 the position shown in Figures 5 and 6, is shown comprising an anti-friction roller 56 rotatably supported in a bracket, generally designated by the numeral 57. The bracket 57 is adjustably secured to the side arm 31, whereby the position 15 of the roller 56 may readily be varied relative to the arm 31 thereby to time the pivotal movement of the cam unit 23 to the operation of the side arm 31, and other associated parts of the mechanism.

20 The mounting bracket 57 of the roller 56 is preferably constructed as shown in Figures 1, 3 and 9, and comprises a body 58 having offset spaced parallel flanges 59 and 61 which embrace the side arm 31. Set screws 62 are mounted in the flanges 25 59 and 61 adapted to engage the opposed edges of the arm 31, and whereby the position of the roller 56 relative to the longitudinal axis of the arm 31 may be varied, if deemed necessary. Clamps 63 cooperate with the set screws 62 to 30 adjustably secure the bracket 57 to the link 31, as will be readily understood by reference to Figures 9 and 10. The anti-friction roller 56 is aligned with the cam faces 28 and 29, as best illustrated in Figure 3, whereby it initially engages cam face 29 and outwardly swings the cam unit 23 to the position shown in Figures 5 and 6, and thereafter roller 56 engages cam face 28, as shown in Figures 7 and 8, each time the side arm 31 goes through a complete cycle of operation, thereby 35 40 to impart to the platen grippers 21, the desired delayed action hereinbefore referred to, as will subsequently be more fully described.

Operation

45 To convert a conventional slow speed press of the type hereinbefore referred to, into a high speed press in accordance with the present invention, the composite cam unit 23, best shown in Figure 11, is pivotally mounted on one of the side frame members of the machine frame in operative relation to the crank disk 33 and side arm 31, as hereinbefore stated, and as illustrated in Figures 1, 2 and 3. The cam unit 23 is preferably aligned with the crank wheel or disk 33 so that the periphery of said disk may be utilized as 50 55 a stop for limiting pivotal movement of the cam unit in one direction, as shown in Figure 4.

A resilient or flexible facing element 70 may be secured to the terminal 60 of the cam unit to prevent metal-to-metal contact between the cam unit and the periphery of the disk 33, when the cam unit is released from the influence of the roller 56 of the side arm 31, as the latter approaches the position shown in Figure 7, wherein the platen has assumed substantially a wide open position. The cam unit 23, it will be noted, is supported in alignment with the crank disk 33 by the U-shaped bracket 25, which constitutes an inherent part of the attachment and is furnished with the composite cam, whereby the operation of mounting the attachment upon the machine frame in correct relation to the crank disk 33 is facilitated.

70 75 The elongated cam face 27 of the composite cam unit 23 cooperates with roller 51 to retain

the platen grippers 21 of the platen in their operative positions in engagement with the printed sheet supported on the platen, and to prevent the grippers 21 from releasing the printed sheet until the platen reaches its open position, shown in Figures 7 and 8. By thus delaying the paper releasing action of the grippers, the pneumatic grippers 22 may engage each printed sheet on the platen preparatory to withdrawing it therefrom before the sheet is likely to become misplaced or otherwise damaged in the operation of transferring the printed sheet from the position shown in Figure 4 to the open position of the platen, shown in Figures 7 and 8.

When mounting the attachment on a press, the roller 51 is aligned with the cam face 27 of the composite cam 23, as shown in Figure 3, whereby said roller is engaged thereby, as will subsequently be described. The roller 51, as hereinbefore stated, has an operative connection with the grippers 21 of the platen 4 through its supporting arm 49, the shaft or rod 52, and the bracket 53. In like manner, the roller 56 carried by the bracket 57 on the side arm 31 is aligned with the cam faces 28 and 29, whereby the roller 56 may oscillate the cam unit 23 to cause the cam face 27 to engage the roller 51 and prevent relative pivotal movement of the grippers 21 relative to the platen, during movement of the platen from closed to open position.

In Figure 4, the platen is shown in its closed position, or in the position assumed when in printing engagement with the bed plate 17. In this position the crank pin 32 of the crank disk 33 is substantially aligned with the axis of the crank disk and the axis of the pivotal connection of the opposite end of the arm 31 with the roller frame member 35, as shown in Figures 1 and 4. Assuming that a sheet has just received an impression, as indicated for example in Figures 1 and 4, as the crank pin 32 moves from position A in Figure 4 to position B in Figure 5, the roller 56 is moved into engagement with the cam face 29, whereby the cam 23 is swung outwardly from the position shown in Figure 4 to that shown in Figure 5 as a result of roller 56 being carried by arm 31. Such outward swinging movement of the cam unit 23 causes its elongated cam face 27 to engage the roller 51 of the grippers 21 and momentarily prevent pivotal movement of the grippers 21 relative to the platen 4, and thus cause them to remain in gripping engagement with the printed sheet independently of the roller 46 and link 37, as in the conventional operation of the machine.

The cam face 27 of cam unit 23 continues to retain the grippers 21 in gripping engagement with the paper while the crank pin 32 advances from position B in Figure 5, to position C in Figure 7. Continued movement of crank pin 32 from position C causes roller 56 to move out of engagement with the cam face 29 whereby the cam unit 23 is returned to its normal position by the action of the spring 59, as shown in Figure 8, and in which position the terminal 60 of the cam unit will engage the periphery of the crank disk 33, as shown in Figure 4. When roller 56 passes over the high point of cam 29, it engages cam face 28 which retards the return movement of cam unit 23, and thus prevents it from impinging against the periphery of the crank disk with any appreciable force.

When the cam unit 23 is thus returned to its normal position, the grippers 21 are permitted to open, after which the pneumatic grippers of the delivery mechanism may engage and withdraw

the printed sheet from the platen, as shown in Figure 8. A fresh sheet of paper may then be delivered onto the platen from the magazine 5, as is well known in the art. From the position shown in Figure 8, the crank pin 32 is returned to position A by the usual operating mechanism of the press, during which movement roller 56 moves out of engagement with cam face 28 and assumes the position shown in Figure 4.

From the foregoing, it will be noted that the simple attachment herein disclosed makes it possible to quickly convert one of the older type, slow operating presses into a high speed press, whereby the capacity of such older presses may readily be made to compare favorably with the output of modern high speed presses.

The invention is extremely simple and inexpensive and does not require that any alterations be made to the press when installing the attachment thereon. The invention comprises very few parts, namely, the composite cam 23 shown in Figure 11, the bracket 25, and pivot bolt 24 for mounting the cam 23 on the machine frame, and a few other parts such as the roller 51, arm 49, shaft 52, mounting bracket 53, and the mounting bracket 57 for roller 56.

The simplicity of the attachment makes it possible to install it on a conventional press in a comparatively short space of time, and when a press is so equipped, the platen grippers 21 of the press will be given a delayed action comparable to that of modern high speed presses, whereby each printed sheet is transferred from its printing position in the machine, shown in Figure 4, to the open position of the platen, shown in Figure 7 with the assurance the pneumatic grippers of the delivery mechanism may engage each printed sheet and withdraw it from the platen without failure.

The foregoing detailed description has been given for clearness of understanding only, and no unnecessary limitations should be understood therefrom, but the appended claims should be construed as broadly as permissible in view of the prior art.

I claim as my invention:

1. The combination with a platen printing press comprising a supporting frame, a platen, means including a crank wheel and a side arm for oscillating the platen between receiving and printing positions, grippers mounted for pivotal movement on the platen and adapted to engage and retain a sheet on the platen, when the platen is in printing position, and operating means for the grippers, said operating means permitting the grippers to open and release the sheet immediately after the sheet has received an impression, of an attachment for retaining the grippers in gripping engagement with the printed sheet during movement of the platen from its closed printing position to its normal open position, said attachment comprising a composite cam unit mounted for pivotal movement on the machine frame, said cam unit comprising an elongated, arcuately formed cam face, the operating means for the grippers including an arm mounted for pivotal movement with the grippers and having a cam follower at its outer swingable end positioned to be engaged by said elongated cam face, whereby oscillation of said cam unit will operate said grippers and retain them in gripping engagement with the printed sheet on the platen during movement of the platen from its closed printing position to its normal open position, said cam unit comprising a second cam face located

in a plane disposed in laterally spaced relation to said elongated arcuately formed cam face, said second cam face comprising dual cam surfaces disposed in end-to-end relation, and a cam follower mounted on the side arm of the press and engageable with said dual cam surfaces to control the swinging movement of the grippers between open and closed positions of the platen, one of said dual cam surfaces swinging the platen and grippers into open position, and the other of said aligned cam faces controlling the return movement of the platen to open position.

2. A printing press according to claim 1, wherein the composite cam unit and its mounting means are constructed independently of the press frame.

3. A printing press according to claim 1, wherein spring means constantly urges the composite cam unit into its normal platen opening position.

4. A printing press according to claim 1, wherein means is provided for horizontally and vertically adjusting the cam follower on the side arm of the press, thereby to facilitate positioning said follower to accurately time the operation of the grippers with respect to the movement of the platen.

CLARENCE B. KLIEVER.
